Primary Examiner — Richard Kearney
Assistant Examiner — Liv C Anderson

(57) **CLAIM**

The ornamental design for a flashlight, as shown and described.

DESCRIPTION

1. Flashlight

- 1.1 : Perspective
- 1.2 : Perspective
- 1.3 : Front
- 1.4 : Back
- 1.5 : Left
- 1.6 : Right
- 1.7 : Top
- 1.8 : Bottom
- 1.9 : Enlarged

The parts shown by means of broken lines in the reproductions are not part of the claimed design; FIG. 1.9 is an enlarged view of the portion taken at line-9 in FIG. 1.2; the dash dot dash lines in FIGS. 1.2, 1.9 and the number 9 in FIG. 1.2 are for the purpose of depicting the cut line of the enlarged view and form no part of the claimed design.

1 Claim, 9 Drawing Sheets
